(57) **CLAIM**

The ornamental design for a rear sling adapter for a firearm, as shown and described.

DESCRIPTION

FIG. 1 is a front perspective view of the rear sling adapter for a firearm showing my new design;

FIG. 2 is a rear perspective view thereof; and,

FIG. 3 is a top plan view thereof.

The sling adapter is installed between the stock and receiver of a firearm, over the buffer tube, and allows a sling or other article to be attached at the point of installation.
